UNITED STATES PATENT OFFICE.

JOSEPH E. GRENIER, OF WATERVILLE, CONNECTICUT.

GAME APPARATUS.

1,132,577.

Specification of Letters Patent.

Patented Mar. 23, 1915.

Application filed December 5, 1913, Serial No. 804,951. Renewed October 15, 1914. Serial No. 866,884.

To all whom it may concern:

Be it known that I, JOSEPH E. GRENIER, a citizen of the United States, and a resident of Waterville, in the county of New Haven and State of Connecticut, have invented certain new and useful Improvements in Game Apparatus, which improvements are fully set forth in the following specification.

The object of this invention is to provide a game apparatus comprising a plurality of localized, correlatively-arranged play-members, each of which shall be markedly simple and inexpensive as regards its construction; and which game shall be well-calculated to test, with more or less severity, the skill, and incidentally the patience, of each user thereof.

The invention consists in certain correlatively arranged play-members, and details of each thereof, whereby the attainment of the foregoing object is rendered feasible, all of which will be hereinafter more specifically referred to and set forth in the appended claims.

25 The invention is clearly illustrated in the accompanying drawing, wherein—

Figure 1 is a diagrammatic view of a game apparatus embodying my said improvements, the various play-members thereof being shown in plan, respectively. Fig. 2 is a view showing in perspective the central play-member made use of. Fig. 3 is a view showing in perspective one of the baffling play-members made use of.

35 Having reference to the accompanying drawing, wherein similar identifying characters denote like parts throughout the several views, I provide a central play-member, hereinafter denominated a central gateway, which comprises a base 2, having upstanding flanges 2', 2'', at its opposite side edges. By preference, each of these flanges is angular in plan, substantially as shown in the drawing, and for a purpose which

45 will appear more clearly hereinafter.

I further provide a plurality of baffling play-members, outlying relatively to the central gateway aforesaid, each of which, hereinafter denominated a baffling goal, comprises a base 3, having a general, U-shaped perimetric contour, and provided, accordingly, with a general U-shaped, upstanding flange 3', whereby a compartment 3'', open at its front and flanked continuously along its opposite side-margins and rear margin, is formed, said base 3 being

further provided with a central pound 4, which may take any appropriate character, as that of a hole formed therethrough or a depression formed therein.

In practice, the central gateway aforesaid is positioned on a suitable bed 4', which may consist of a floor, or an appropriate section thereof, the various baffling-goals aforesaid being then positioned on said bed, and arranged, suitably spaced each from its neighbor or neighbors, more or less concentrically to said gateway, each being suitably removed therefrom, and presenting, by preference, its open front in the direction thereof.

I contemplate the employment of five of the baffling-goals aforesaid, four of them being so positioned on the general bed 4' as to occupy, respectively, the angles of a quadrangular figure uniformly inclosing the central gateway aforesaid, the additional, or fifth, one being positioned on said general bed rearwardly of said central gateway, and approximately midway between that pair of said baffling-goals there situated, and occupying, respectively, opposite angles of the figure aforesaid.

It may be here pointed out that the angular, upstanding flange 2', 2'', of the central gateway aforesaid, have, by preference, each a coöperative relation, as will herein-after become apparent, with such pair of the baffling-goals as shall occupy angles of the rectangular figure aforesaid obliquely opposite, by preference, to the gateway aforesaid, said flanges standing, each in whole or in part, intermediate of such obliquely situated baffling-goals and in registry lengthwise therewith, respectively.

As here shown, each of the flanges 2' 2'' comprises a pair of angularly-arranged, constituent sections, one of which stands intermediate of, and in registry lengthwise with, a pair of the baffling-goals occupying opposite angles, in one direction obliquely along the rectangular figure aforesaid, and relatively to said gateway, and the other of which stands intermediate of, and in registry lengthwise with, the remaining pair of said baffling-goals, occupying the remaining opposite angles, in the opposite direction obliquely along said figure, and relatively to said gateway.

The several unitary parts of my improved game apparatus having been duly positioned, as on the general bed 4', a spherical

object or ball 5, is placed thereon forwardly of the central gateway, and approximately midway the opposite baffling-goals there situated, substantially as indicated in the drawing. Whereupon, the user, through the medium of a suitable mallet or the like, strikes the ball in a manner to cause the same to roll with more or less rapidity in the direction of the gateway aforesigned, and in an attempt to cause the same to pass through said gateway, and continue to move, say, in the general direction of the baffling-goal occupying that angle of the figure aforesigned, beyond said gateway, and most distant from, and to the right of the user, the latter considered as standing in front of, and facing such gateway. In thus attempting to cause the ball 5 to approach the baffling-goal last referred to, the user may be materially aided by causing said ball to primarily impinge against, say, that section of the flange 2' which stands in registry lengthwise with such baffling-goal, the ball caroming from said flange-section, and being diverted thereby into a course of movement leading in the general direction of said baffling-goal. The user may be limited to a definite number of attempts for causing the ball to thus reach and enter said baffling-goal, as by way of its open front; and when he shall have accomplished this end, said ball, an adequate propelling force being imparted thereto, may engage the U-shaped, upstanding flange of said goal, follow, say, along the same, at the inner face thereof, and either ultimately take a return movement and escape from such goal, or casually find lodgment in the pound thereof. Should the ball escape from said baffling-goal the user may be privileged to make a like number of attempts, preferably under the restriction, now of first causing the ball to make a return movement through the gateway aforesigned, to cause said ball, in substantially the manner above explained, to enter and escape from another baffling-goal, without finding lodgment within the pound thereof; and so on, until the user shall have caused the ball to visit, accordingly, each of the several baffling-goals made use of, and in any predetermined or desired order.

Should the ball casually find lodgment within the pound of any of the baffling-goals made use of, the user may be required to redeem the ball, replace it at the starting point aforesigned, and recommence his playing operations.

The apparatus may be availed of by any reasonable number of users, playing in turn; and it is evident that various games, other than the one above outlined, may be devised and amusingly played with the aid of said apparatus.

The terms rearwardly and forwardly herein appearing, apply to the parts of my

improved apparatus, and the positioning thereof, in their relation, respectively, to the point, above referred to, on which the ball 5, is primarily placed, such point being treated as situated forwardly of the apparatus; and any appropriate material, as wood or metal, or both, in sheet-form, may be used in constructing said parts, respectively.

It will be seen that my improved game apparatus is well adapted for the purposes for which it is intended, and further that the same may be modified to a considerable extent, particularly as regards the specific form of either of the upstanding flanges 2', 2'', the specific character of any of the baffling-goals made use of, so long as the same is capable of receiving, returning, and casually impounding the ball or spherical object made use of, the general arrangement of said baffling-goals, or any thereof, relatively to the central gateway made use, and various minor details of the separate parts of my improved apparatus, without materially departing from the scope of my invention, as defined in the claim or claims hereto appended.

I claim:

1. A game apparatus comprising a bed; a central gateway thereon; a baffling-goal also thereon, and arranged relatively to said gateway; and an object adapted to be rolled along said bed, said baffling-goal adapted to receive, and either return or casually impound said object. 95
2. A game apparatus comprising a bed; a central gateway thereon; a plurality of baffling-goals also thereon and arranged more or less concentrically to said gateway; and an object adapted to be rolled along said bed, said baffling-goals being each adapted to receive, and either return or casually impound said object. 100
3. A game apparatus comprising a bed; a base centrally thereon, affording opposite flanges, and constituting a gateway; an additional base, positioned on said bed relatively to said gateway, and affording a flange whereby an opening compartment is formed, an constituting a baffling-goal; and an object adapted to be rolled along said bed, said baffling-goal adapted to receive and return said object. 110
4. A game apparatus comprising a bed; a base thereon affording an upstanding flange, and constituting a gateway; a baffling-goal positioned thereon relatively to said gateway; and an object adapted to be rolled along said bed, said baffling-goal adapted to receive and either return or casually impound said object, and the upstanding flange aforesigned being in registry lengthwise with said goal. 120
5. A game apparatus comprising a bed; a base thereon affording opposite, upstand- 130

ing flanges and constituting a gateway; a plurality of baffling-goals, positioned on said bed more or less concentrically to said gateway, and an object adapted to be rolled along said bed, each of the upstanding flanges aforesaid being in registry with a pair of said baffling-goals situated diagonally opposite said gateway, and each of

said goals being adapted to receive and either return or casually impound said object.

JOSEPH E. GRENIER.
